UNITED STATES PATENT OFFICE

159,238

VEHICULAR TANK

Clifford Brooks Stevens, Milwaukee, Wis., assignor to The Heil Co., Milwaukee, Wis., a corporation of Wisconsin

Application September 14, 1949, Serial No. 4,988

Term of patent 14 years

(Cl. D14—3)

To all whom it may concern:

Be it known, that I, Clifford Brooks Stevens, a citizen of the United States, residing at Milwaukee, in the county of Milwaukee and State of Wisconsin, have invented a new, original and ornamental Design for a Vehicular Tank, of which the following is a specification, reference being had to the accompanying drawing forming part thereof.

Fig. 1 is a rear and side perspective view of the vehicular tank showing my new design; and

Fig. 2 is a rear view thereof.

The characteristic features of my design reside in the portions shown by means of full lines in the drawing.

I claim:

The ornamental design for a vehicular tank, substantially as shown and described.

CLIFFORD BROOKS STEVENS.
